CLAIM

I claim the ornamental design for compartmentalized pouch
with perpendicular frangible walls, as shown and described.

DESCRIPTION

FIG. 1 is a perspective view of a compartmentalized pouch
with perpendicular frangible walls showing my new design;
FIG. 2 is a front view thereof;
FIG. 3 is a back view thereof;
FIG. 4 is a right side view thereof;
FIG. 5 is a left side view thereof;
FIG. 6 is a top view thereof; and,
FIG. 7 is a bottom view thereof.
